UNITED STATES PATENT OFFICE.

HENRY CHARLES WHITE, OF PHILADELPHIA, PENNSYLVANIA, ASSIGNOR TO THOMAS DEVELON, JR., OF PHILADELPHIA, PENNSYLVANIA.

DESIGN FOR A RUG.

No. 40,168.

Specification for Design.

Patented July 20, 1909.

Application filed May 25, 1909. Serial No. 498,376. Term of patent 3½ years.

To all whom it may concern:

Be it known that I, HENRY CHARLES WHITE, a subject of the King of Great Britain, residing in the city of Philadelphia, State of Pennsylvania, have invented a certain new, original, and ornamental Design for Rugs, of which the following is a specification, reference being had to the accompanying drawing, wherein is shown in plan view a quarter-section of said design on a

Wilton rug, the other three-quarters of the design being identical therewith.

I claim:—

The ornamental design for a rug, substantially as shown.
